Walton Harrison

UNITED STATES PATENT OFFICE.

ARTHUR MUTSCHELLER, OF NEW YORK, N. Y., ASSIGNOR TO WAPPLER ELECTRIC COMPANY, INC., A CORPORATION OF NEW YORK.

SAFETY DEVICE FOR VACUUM TUBES.

Application filed July 17, 1919. Serial No. 311,518.

To all whom it may concern:

Be it known that I, ARTHUR MUTSCHELLER, a citizen of the United States, residing at New York, county of New York, and State of New York, have invented certain new and useful Improvements in Safety Devices for Vacuum Tubes, of which the following is a full and concise description.

My invention relates to safety devices for vacuum tubes, my more particular purpose being to protect the vacuum tube from breakage or other injury due to the use of an electric discharge within the tube.

More particularly stated, my invention relates to safety devices for vacuum tubes of the type commonly employed in X-ray photography and fluoroscopy and in which an electric discharge takes place inside of a glass tube, under conditions such that some portion of the tube is likely to be broken by excessive heat from the cathode, or otherwise injured by continuous bombardment by cathode rays. By my invention I seek to avoid the difficulties just mentioned.

An X-ray tube, as ordinarily constructed, comprises among other things a globular member of glass provided with a pair of glass necks integral with it and extending in opposite directions. One of these necks supports the anode and the other the cathode.

In the use of the tube, the neck supporting the cathode is exposed to danger of breakage, owing to the excessive heat developed by the cathode rays. When a fracture occurs it usually takes place in the neck which houses the cathode, and in that portion of the neck where the cathode rays are most active when in consequence there is excessive heating.

The danger of breakage from the cause just stated is increased if the inner surface of the tube has become encrusted with metal, deposited from metallic vapors formed from either the cathode or the anticathode.

Again, it often happens that the X-ray tube acts abnormally even when apparently uninjured, owing to conditions brought about by the action of the cathode rays, and particularly to the presence of metallic de-

posits upon the internal surface of the neck in which the cathode is housed.

Heretofore in this art it has been customary to place a metallic shield, in the form of a cylinder, around the cathode in order to protect the glass neck in which the cathode is housed. This shield is designated as a cathode shield. It tends to protect the wall of the glass neck against bombardment by cathode rays, and against leakage from the cathode to the glass neck. Sometimes this shield is placed in direct metallic contact with the cathode, yet not in direct contact with the glass neck. In some instances the shield is spaced about midway between the cathode and the wall of the glass neck. In other instances the shield is placed in contact with the glass wall of the neck.

With the shield arranged in either of the three ways just mentioned, however, a puncture of the glass wall of the neck is liable to occur at any moment while the tube is in use.

Not only that, but the cathode shield is also liable to be pierced by electric discharges taking place from the shield to the glass wall and such discharges are easily set up owing to the formation of metallic deposits produced within the tube.

Because of the facts above stated the metal shield, if located as heretofore, does not afford adequate protection against breakage of the tube.

I have made this discovery, that by following certain principles hereinafter discussed, it is possible to determine for the shield a definite form and a relative position in which it can afford adequate protection to the tube.

I have ascertained from observation, based upon experiment, that the cathode shield must be so located as to intercept all cathode rays emanating from the sides and rear portion of the cathode, and also as far as possible all cathode rays tending to pass directly from the concave face of the cathode to the adjacent inner surface of the glass neck in which the cathode is located.

By making the cathode shield a little longer than usual, and projecting or extending it slightly past the concave end of the

cathode, I find it practicable to cut off most of the cathode rays tending to pass from the concave face of the cathode to the adjacent inner surface of the glass neck; and thus it is practicable to prevent discharges from the edge of the cathode to the glass neck.

I also make provision to prevent the cathode shield from accumulating an undue potential.

Reference is made to the accompanying drawing forming a part of this specification, and in which like reference characters indicate like parts in both of the figures.

15 Figure 1 is a side view, partly in side elevation and partly in section, of an X-ray tube equipped with my invention.

Figure 2 is an enlarged central section through the cathode shield and parts immediately associated therewith.

20 A glass bulb 3 is provided with two tubular necks 4, 5, made of glass and integral with the bulb. The necks 4, 5, are designated respectively as the anode neck and the cathode neck.

The anode is shown at 6 and may be of the usual or any desired construction.

25 The cathode appears at 7 and is made of suitable metal, preferably aluminum. It is provided with a cylindrical portion 7^a of reduced diameter and with a concave face 7^b; also with a cupped edge 7^c bounding this face.

30 The cathode is secured upon a conductor 8, in the form of a metallic rod. This rod extends axially through a supporting tube 9 made of glass and carrying two annular members 10, 11 made also of glass, and disposed concentrically.

40 The general diameter of the portion 7^a of the cathode is the same as the external diameter of the annular member 10.

45 Fitted partly upon the annular member 10 and partly upon the portion 7^a of the cathode is a sleeve 12, made of iron and having the general form of a hollow cylinder.

50 The cathode shield is shown at 14, and has a general cylindrical form. It is made of metal, preferably either steel, copper or aluminum, and is fitted upon the annular member 11, whereby it is supported. The cathode shield is provided with a portion 14^a of greater diameter than the portion in actual contact with the annular member 11.

55 A metallic tongue 15, of platinum, steel or any other appropriate metal is by means of rivets 16 mounted upon the inner surface of the cathode shield. This tongue extends into close proximity to the adjacent surface of the iron sleeve 12. An adjusting screw 17 extends loosely through a hole in the cathode shield and makes a working engagement with the tongue 15, through which it extends. By means of the screw 17, the tongue 60 15 is adjusted relatively to the iron sleeve 12.

This is done, of course, before the tube is sealed or exhausted.

The adjustment is such that the distance between the iron sleeve 12 and the nearest adjacent portion of the tongue 15 is less than the distance between the cupped edge 7^c of the cathode and the nearest adjacent portion of the cathode shield. By this arrangement no sparking can take place between the cupped edge 7^c and the cathode shield. Hence, though the cathode shield becomes electrically charged from the action of the cathode rays, it is repeatedly discharged, as any charge accumulating upon it passes from the free end of the tongue 15 to the iron sleeve 12, and thence to the cathode, during the intervals between the main discharges taking place through the tube. Under no conditions, however, can any discharge take place from the cathode shield to the glass wall of the cathode neck 5 even if the inner surface of the cathode neck be encrusted or frosted with metal. This is because the distance from the cathode shield to the nearest adjacent portion of the cathode neck is too great to allow such discharge to take place between the impulses. I find that the distance from the cathode shield to the nearest adjacent portion of the cathode neck should be at least three times the shortest distance between the cathode and cathode shield.

55 My arrangement of the parts as described accomplishes another good purpose, in that it has a tendency to prevent the formation of excessive quantities of metallic vapors in the X-ray tube, and also to prevent the accumulation of such vapors in that portion of the tube adjacent the concave face of the cathode.

60 Without the tongue 15 it would not be possible to prevent electric discharges from taking place from the cathode shield to the iron shield and thus to the cathode, under such conditions as to liberate metallic vapors in close proximity to the concave face of the cathode. Such vapors have a tendency to render the action of the tube anomalous or freakish, and are of course undesirable. By my arrangement, however, I reduce the production of the metallic vapors and prevent them from reaching the concave face of the cathode. In my construction and arrangement of the parts there is no tendency toward the formation of such vapors except at the point where small discharges take place from the tongue 15 to the adjacent surface of the iron sleeve 12, or in other words, within the cathode shield 14. The point where this takes place is cool and remote from the concave face of the cathode and in a region where the temperature is relatively low. The conditions surrounding the discharge in question are such that the vapors are condensed and thus prevented from getting into the main body of the

tube; that is, into the bulb 3. In practice it is found that the metals of the vapors thus formed are forthwith deposited upon the surface of the iron sleeve 12, in close proximity to the point of the tongue 15. Thus the formation of the vapors is localized, and the vapors are to all intents and purposes destroyed as formed and thus rendered harmless.

10 The parts are so proportioned and arranged as to reduce, as far as practicable, the number of cathode rays reaching the glass wall of the cathode neck 5 from the concave face 7^b or from the cupped edge 7^c or any

15 rear portion of the cathode.

I find in practice that if cathode rays pass directly and in straight lines from the concave face 7^b and from the cupped edge 7^c to a portion of the cathode neck immediately 20 adjacent, such portion is heated quite rapidly and to a high temperature, thus increasing the danger of breakage. I therefore place the cathode and the cathode shield in such positions relatively to the cathode neck 5 and to each other as to prevent as far as practicable this result. Following this idea, I place the cathode far enough to the left according to Figures 1 and 2 to leave the cupped edge 7^c a 25 little short of the left end of the cathode neck 5. In so doing I place the cathode shield so far to the left that its left end overlaps the adjacent cupped edge of the cathode to an extent sufficient to cut off 30 most, or at least a large proportion, of such rays from the concave face of the cathode as would otherwise fall upon the adjacent inner surface of the glass cathode neck.

35 The operation of my device is as follows: 40 The parts being assembled and arranged as shown in the drawing and as above described, the X-ray tube is mounted in position, and electric discharges are sent through it in the usual or any desired manner so as to produce Roentgen or X-rays.

45 The cathode shield effectively protects the inner surface of the glass cathode neck from the cathode rays, and thus prevents overheating of the cathode neck and consequent breakage of the X-ray tube. The cathode shield, because of its position relatively to the cathode, serves to prevent the cathode rays from the concave face of the cathode and any rear portion thereof from 50 reaching the adjacent encircling portion of the cathode neck, in sufficient quantities to overheat such portion. Differences of potential developing between the cathode shield and the cathode are neutralized by 55 discharges which are localized as above described, and all metallic vapors generated by such discharges are condensed at a point remote from the bulb 3 of the X-ray tube, and thus are localized along with the 60 discharges.

An X-ray tube made as above described can be operated continuously and under comparatively high voltages and with heavy currents for long periods of time, without danger of breakage from over heating of the cathode neck, and without developing trouble due to excess of metallic vapors within the tube.

65 My invention is not intended to be limited to use upon X-ray tubes, as manifestly it can be employed upon any vacuum tube in which a glass neck or analogous member is to be shielded from the cathode rays and thus protected from overheating.

I claim:

1. In a safety device for X-ray tubes the combination, with an exhausted glass cathode neck and a cathode shield and cathode located within said cathode neck, of a discharge gap located within said exhausted cathode neck and provided with means for localizing, at a particular point, the discharges from said cathode shield to said cathode.

2. In a safety device for vacuum tubes the combination, with a metallic cathode and an evacuated hollow member enclosing said cathode, of a cathode shield having a portion extending directly between said cathode and an adjacent portion of said hollow member, and means for localizing the formation and condensation of metallic vapors within said hollow member.

3. In a device of the character described the combination of an exhausted vessel containing a cathode and a cathode shield, of means for localizing the formation of objectionable vapors within said exhausted vessel, in a predetermined region relatively to said cathode.

4. In a vacuum tube the combination, with an exhausted vessel, a cathode mounted therein and provided with a terminal face, and a cathode shield mounted within said exhausted vessel, of means located within said exhausted vessel for localizing the condensation of vapors in a portion of said exhausted vessel remote from said terminal face.

5. In a vacuum tube the combination, with an exhausted vessel and a cathode and a cathode shield mounted within said exhausted vessel, of means for facilitating a discharge within said exhausted vessel, at a predetermined point between said cathode and said cathode shield.

6. In a vacuum tube the combination, with an exhausted vessel and a cathode and a cathode shield mounted therein, of a tongue made of conducting material and mounted upon said cathode shield, said tongue being located within said exhausted vessel and extending toward said cathode in order to facilitate discharges from said cathode shield to said cathode.

7. In a vacuum tube the combination of adjacent portion of said cathode neck in an exhausted bulb provided with a neck extending from said bulb and communicating therewith, a cathode mounted within said neck and provided with a terminal face, a cathode shield mounted within said neck and provided with a portion extending intermediate said cathode face and the nearest rays, and means for facilitating discharges from the cathode shield to the cathode, the space between the cathode shield and the neck being sufficient to prevent discharges taking place therebetween.

ARTHUR MUTSCHELLER.
